UNITED STATES PATENT OFFICE.

BLANCHE SMITH PIERCE, OF GRAND RAPIDS, MICHIGAN.

SERVICE-COVER FOR MILK-BOTTLES, JARS, &c.

1,132,615.

Specification of Letters Patent. Patented Mar. 23, 1915.

Application filed October 23, 1913. Serial No. 796,780.

To all whom it may concern:

Be it known that I, BLANCHE SMITH PIERCE, a citizen of the United States of America, residing at Grand Rapids, in the county of Kent and State of Michigan, have invented a new and useful Improvement in Service-Covers for Milk-Bottles, Jars, &c., of which the following is a specification.

My invention relates to improvements in covers for bottles, jars, etc., and more particularly to special covers to close the orifices of such vessels while in service after the regulation cover, cap or seal provided for closing same has been removed.

The objects of my invention are to provide a device for the purpose which is simple, durable, efficient, easily cleaned and sterilized, easy and cheap to manufacture, and capable of being applied or removed by hand without the use of any tool. These and other objects of my invention will more fully appear from the following description.

My invention consists essentially of the various novel features of construction and arrangement of parts hereinafter more fully described and particularly pointed out in the claims, reference being had to the accompanying drawings illustrating a device embodying my invention and the best mode contemplated by me for applying my invention in practice.

A cover constructed in accordance with my invention consists of a single piece of suitable material, as, for example, commercial sheet aluminum or tin, having an annular flat portion for contacting with the annular top surface adjoining the orifice of the vessel; an annular stiffening rim at the exterior of the flat annular contacting portion; and two diametrically opposite clamping portions in the form of lugs or ears, depending from the edge of the annular stiffening rim, to elastically engage the exterior side surfaces adjacent the orifice of the vessel and thus hold the cover in place against light accidental forces tending to dislodge it. Preferably, to further assist in maintaining the flatness of the annular contacting portion, the central portion, within the flat annular contacting portion, is offset from the plane of the flat contacting portion.

The material from which the cover is made is preferably somewhat elastic or springy and the clamping lugs are prefer-

ably so shaped as to conform approximately to the exterior form of the sides of the orifice of the vessel adjacent its top. This construction renders it easy to apply the cover to or remove it from the orifice of the vessel by hand, without any tool, and it also provides for automatically adapting the cover to such variances in the external form and diameters of the orifices of the vessels of a standard type and size as is commonly met with in the commercial production of such articles.

A cover made in accordance with my invention is not designed to be used as a leak-proof closure to the orifice of the vessel, as is the regulation cover, cap or seal provided for that purpose for certain bottles, jars, etc., but it is designed to be used as a service cover for the orifice of the vessel so as to protect its contents from dust, insects, etc., after the regulation cover, cap or seal has been removed and its replacement is not desired. For example, the seal generally used for bottles in which milk and cream are delivered to the consumer consists of a disk of rather heavy and soft cardboard which fits snugly in a suitable internal recess forming the top of the orifice of the bottle. In opening a bottle thus sealed a sharp instrument is generally used to pry the seal out of its recess, with the result that the seal is generally so injured in its removal as to render it inadequate or at least undesirable for further service, and such a seal is generally discarded upon its first removal from the bottle. When the regulation seal has been removed from such a bottle the contents of the bottle are available for service as needs may require from time to time, and the bottle may then be said to be in service. It is during the period while the bottle is thus in service and its contents being drawn upon as desired that my special cover is put in service on the bottle to protect its remaining contents—hence I have appropriately designated it a "service cover."

Referring now to the accompanying drawings: Figure 1 is a top view of one form of my improved cover; Fig. 2 is a side view of the upper portion of a common milk bottle having my improved cover, partly in section, thereon; Fig. 3 is a vertical central section on line A—B of Fig. 2; Fig. 4 is a central cross-section of my improved cover showing the central portion

- depressed instead of raised, as is shown in the other figures; Figs. 5 and 6 are side views, partly in section, of a form of my improved cover, showing an additional ear 5 forming a limit stop and facilitating the engagement and disengagement of the cover from the vessel; Figs. 7 and 8 are side views of my improved cover as applied to a jar or common tumbler.
- 10 Like numbers refer to like parts in all of the figures.
- Of the parts: 1 is the flat annular portion which contacts with the annular top surface adjoining the orifice of the vessel; 2 is the annular rim formed integrally with and exterior to part 1 to stiffen same; 3 is the pair of oppositely disposed lugs, depending from and formed integrally with part 2, which by their clamping action hold 15 the cover in place over the orifice; 4 is an additional lug or ear employed in one form of my device, depending from the rim 2, as shown in Figs. 5, 6, 7 and 8, which facilitates the engagement and disengagement of the 20 cover from the vessel; 5 is the central raised or depressed portion within part 1, and 6 is the annular offset formed integrally with and joining parts 1 and 5 and serves to aid in maintaining the flatness of part 1 against 25 its accidental deformation.
- 30 Sanitary considerations require that the cover be of such form in its several parts as to avoid the formation of recesses or corners difficult of access for thorough cleaning.
- 35 To satisfy that requirement in my improved cover the annular stiffening rim 2 and the offset 6 are preferably not formed abruptly, but as shown in the sectional portions of Figs. 2 and 6.
- 40 The annular curved rim 2 is not designed to make contact with the bottle or jar, but serves simply to stiffen the flat contacting portion 1. The rim 2, therefore, preferably stands away from the bottle a small 45 amount as shown at 7 in the sectional portion of Fig. 2. This provision insures that the flat contacting portion 1 may be made wide enough to adapt one size of the cover successfully to the top of bottles of a standard type and size by allowing for the variations commonly met with in their commercial production. Additional stiffening of the cross-section of the cover may evidently 50 be provided by forming annular corrugations in parts 1 and 5, but as such corrugations would make the cleaning of the cover more difficult I prefer to avoid their employment and instead thereof to increase the amount of the offset 6 and the depth of the 55 annular rim 2 as much as may be necessary to provide any desired degree of stiffness of the cross-section.
- 60 By making the form of lugs approximately that of the surfaces against which they bear, the form of their section, in

planes parallel to surfaces 1 and 5, is such as to aid materially in stiffening the lugs and providing against their accidental deformation, and this stiffening aids materially in providing the desired clamping action of the lugs in holding the cover in place.

When used with a bottle having a bead formed on the exterior of its neck adjoining its top, as shown in Figs. 2 and 3, my improved cover is preferably applied to or removed from the bottle by moving the cover in a plane practically parallel to its flat surfaces and in a direction at right angles to a line through the middle of the lugs 3. 70 When used with a jar having a top similar to that shown in Figs. 7 and 8, my improved cover may be applied or removed in the manner above described or by vertical movements as may be preferred by the user.

75 The lug 4 facilitates the placing of the cover on the bottle by affording a good surface against which to press when forcing the clamping lugs 3 into proper engagement with the sides of the vessel, and it also 80 facilitates the engagement by forming a stop which prevents forcing the cover too far over when applying it. The disengagement of the cover is facilitated by the lug 4 which affords a hold for the tips of the 85 fingers or nails when withdrawing the cover from the bottle.

90 Variations in the forms of the elements of my invention, from those specifically shown and described above, may be made without departing from the essentials of those elements or of the invention as a whole, and I would include as within the scope of my invention such available variations in the 95 form of its elements as may be found desirable in adapting it to its various possibilities of service.

100 I declare the above to be so full and clear a specification of my invention as to enable others skilled in the art to which it pertains to make and use the same.

110 What I claim as my invention is:

115 1. A service cover for a bottle, jar or other vessel, comprising, in a single piece of suitable thin and flexible sheet metal, an annular vessel-top-contacting portion, a pair of oppositely disposed securing lugs depending from the outer edge of the vessel-top-contacting portion, and a third lug also 120 depending from the outer edge of the vessel-top-contacting portion, and located midway circumferentially thereon between the two securing lugs, to facilitate the manual application of the cover to and its removal from the top of the vessel, substantially as 125 shown and described.

130 2. A service cover for a bottle, jar or other vessel, comprising, in a single piece of suitable thin and flexible sheet metal, an annular vessel-top-contacting portion, an

- annular stiffening rim portion external to the said annular contacting portion, a pair of oppositely disposed securing lugs depending from said external annular stiffening rim portion, a raised portion within the annular vessel-top-contacting portion whereby an annular offset is provided at the junction of the two last named portions for the purpose of further stiffening the cover, and 15
5 a third lug depending from the external annular stiffening rim portion, and located midway circumferentially thereon between
10 the two securing lugs, to facilitate the manual application of the cover to and its removal from the top of the vessel, substantially as described.
- In testimony whereof I affix my signature to this specification in the presence of two witnesses.

BLANCHE SMITH PIERCE.
